UNITED STATES PATENT OFFICE.

ALBERT C. WETHERBEE, OF HAMMONTON, NEW JERSEY, ASSIGNOR OF
ONE-HALF TO ALEXANDER AITKEN, OF SAME PLACE.

THILL-CO尤LING.

SPECIFICATION forming part of Letters Patent No. 274,428, dated March 20, 1883.

Application filed January 10, 1883. (No model.)

To all whom it may concern:

Be it known that I, ALBERT C. WETHERBEE, a citizen of the United States, residing at Hammonton, in the county of Atlantic, State of New Jersey, have invented a new and useful Improvement in Thill or Shaft Couplings, which improvement is fully set forth in the following specification and accompanying drawings, in which—

10 Figure 1 is a top or plan view of the thill or shaft coupling embodying my invention. Fig. 2 is a section thereof in line *xx*, Fig. 1. Fig. 3 is front view thereof, and Fig. 4 is a bottom plan thereof.

15 Similar letters of reference indicate corresponding parts in the several figures.

My invention relates to improvements in a thill or shaft coupling so constructed that should the bolt thereof break or be lost the coupling will remain connected sufficiently for all purposes until another bolt is applied. For this purpose the lower end of the thill-iron is formed with an integral head wider than the space between the side pieces of the box, which, 25 when the bolt is broken or lost, is adapted to engage with the sides of the box, and thus provide a temporary coupling, as will be herein-after set forth.

Referring to the drawings, A represents the arm or iron of a thill-coupling; B, the box, bearing, or support to which said iron is bolted, and C the clip with which said box is connected.

On the lower end of the iron is formed a head, D, which extends transversely below the box, and is of width greater than the space between the sides, so as to project under the sides, as shown in Figs. 3 and 4.

In order to permit the passage of the head D through the box, the inner face of each side, at the front thereof, is recessed or grooved in a vertical direction, as at *a*, it being noticed that the sides of the box are connected in front by the piece *b*.

45 It will be seen that when the parts are in operative position, as in Fig. 2, the coupling renders usual service. When, however, the bolt *B'* is broken or lost, the iron released from the sides of the box is carried forward, limited

by the front piece of the box, and the projecting ends of the head D abut against the lower sides of the box, thus controlling said head, whereby the iron remains connected with the box, providing a temporary coupling, which is sufficient for all purposes until a new bolt is supplied, it being seen that the box is open from top to bottom and readily receives the eye of the iron and the rubber block or packing similar to couplings in use, and that I employ an ordinary bolt and nut for connecting the iron and box. Furthermore, the vertical groove *a* extends throughout the box from top to bottom, so that when the cross-head D is passed down through said groove and moved back under the side walls the eye of the coupling is in position to receive the bolt.

I am aware that it is not new to form a thill-iron with trunnions which are fitted in ears rising from a base-plate of a coupling, and to connect with said iron a bent spring which is passed through an opening in said base-plate, and has on its lower end an arrow-head.

I am also aware that it is not new to form the lower end of a thill-iron with an upwardly-projecting hook which enters a recess in the coupling-box from below, and provide said iron with studs which are fitted in other recesses in the iron, the forward bifurcated end of the box being clamped by a bolt and nut; but in both such constructions the ordinary securing and pivotal bolt and nut are undesirably dispensed with and weak and complicated boxes are presented; and neither of them shows a box closed in front by a wall cast or formed with the side walls, or a head integral with the iron at the lower end, below the side walls of the box, and wider than the space between said side walls, wherefore I have made an improvement in the art.

Having thus described my invention, what I claim as new, and desire to secure by Letters Patent, is—

1. In a thill-coupling, a box, in combination with a thill-iron having its lower end, below said box, formed with a head which is wider than the space between the side pieces of the box and integral with said iron, substantially as and for the purpose set forth.

2. In a thill-coupling, a thill-iron provided at its lower end with a head, in combination with a coupling-box having a front wall which is formed with the side walls, substantially as and for the purpose set forth.

3. A box having a front wall continuous with the side walls thereof, and provided with a vertical groove open from top to bottom, the connecting-bolt of the iron and box, and a thill-iron having at its lower end a head which

is of greater width than the space between the side walls and integral with the iron, combined and operating substantially as described, and forming an improvement in thill-couplings.

ALBERT C. WETHERBEE.
